UNITED STATES PATENT OFFICE.

GEORGE J. KRANSHAAR, OF CLEVELAND, OHIO.

OILER.

SPECIFICATION forming part of Letters Patent No. 529,921, dated November 27, 1894.

Application filed May 17, 1894. Serial No. 511,555. (No model.)

To all whom it may concern:

Be it known that I, GEORGE J. KRANSHAAR, a citizen of the United States of America, residing at Cleveland, in the county of Cuya-

5 hoga and State of Ohio, have invented certain new and useful Improvements in Oilers, of which the following is a specification, reference being had to the accompanying drawings.

10 This invention relates to certain new and useful improvements in oilers and particularly to those used for oiling shafting, the following being such a full, clear and exact description of the invention as will enable those skilled in the art to which it pertains to make and use the same.

The object of the invention is to produce an oiler having a sectional spout whereby shafting and bearings of varying heights may 20 without the aid of a ladder be readily reached; furthermore, in producing an oiler provided with means for forcing the contents through the spout when retained in a vertical position.

5 The invention has for a still further object the provision of means for retaining the oil in the spout and for discharging the same when desired.

With these and other objects in view the 30 invention consists in the construction of an oiler that shall possess advantages in points of simplicity and general efficiency.

Finally the invention consists in the various novel details of construction, arrangement and combination of parts to be herein-after more fully described and specifically pointed out in the claim.

In describing the invention in detail reference is had to the accompanying drawings 40 forming part of this specification, wherein like characters of reference indicate corresponding parts in the several views, in which—

Figure 1, is a view in side elevation of my improved oiler. Fig. 2, is a detail view of a 45 section of the spout showing the connections. Fig. 3, is a sectional view of a part of the spout showing the check valve and drain, and Fig. 4, is an enlarged detail view of the pump valve and sucker.

50 In the drawings, 1, denotes the casing of the tank provided with a handle which is made hollow to receive a supplemental handle when

it is necessary to reach shafting of unusual height. The handle is also provided with a set screw 3, by which the supplemental handle is secured when adjusted. 55

The casing has secured on the side thereof a pump 4, communicating with the interior through the connecting pipe 5. The piston or sucker rod 6, works through the stuffing box 60 7, and is encircled by a coil spring by which it is held normally elevated with its end bifurcated to receive the lever 8, said lever being secured in a loop 8^a, on the spout (to be hereinafter referred to) and ending in a right angular lug to prevent its pulling out. The opposite end of the lever is provided with an operating rod 9, and chain 10, although the rod or chain may be dispensed with and any substitute therefor applied. 70

Leading from the tank is a spout 11, connected with the pump by the pipe 12. The spout consists of sections secured together by means of screw threads with the flanged collars 13, which are provided to form a tight joint and present a neat appearance as well as to strengthen the said spout. The top of the spout 14, is angular to allow ready application to the oil-cup of the shafting. The angular end can be secured directly to the can 75 dispensing with the intermediate sections, thus making an ordinary oiler when desired. 80

Interiorly the spout is provided with a valve 15, which retains the oil in the spout, that by a slight working of the pump it may be forced 85 out of the top.

The drain 16, connects the spout and can proper and is provided with a stop cock 17, that the oil may be drained from the spout when not in use; said drain being connected 90 with the spout just above the valve.

It will be noted in view of the foregoing that various changes may be made in the detail construction of the device without departing from the general idea involved. For 95 instance instead of having the sections of the spout formed as shown, they may be telescopically connected as will be apparent.

Having fully described my invention, what I claim as new, and desire to secure by Letters 100 Patent, is—

In an oiler, the combination with the reservoir having an adjustable spout and a hollow handle to receive a supporting rod, a valve

in the spout, a drain leading from the spout above the valve and communicating with the reservoir, a stop cock in said drain, a pump secured to the exterior of the reservoir and 5 communicating therewith by means of the pipe, a connecting pipe between the pump and spout, a spring encircling the sucker rod of the pump to hold the same normally elevated, a lever secured to the sucker rod, hav-

ing a flexible connection by which it is operated, as and for the purpose described.

In testimony whereof I affix my signature in presence of two witnesses.

GEORGE J. KRANSHAAR.

Witnesses:

J. H. MCARTHUR,
M. J. MCARTHUR.

It is hereby certified that the name of the patentee in Letters Patent No. 529,921, granted November 27, 1894, for an improvement in "Oilers," was erroneously written and printed "George J. Kranshaar," whereas said name should have been written and printed *George J. Kraushaar*; and that the said Letters Patent should be read with this correction therein that the same may conform to the record of the case in the Patent Office.

Signed, countersigned, and sealed this 18th day of December, A. D. 1894.

[SEAL.]

JNO. M. REYNOLDS,
Assistant Secretary of the Interior.

Countersigned:

JOHN S. SEYMOUR.
Commissioner of Patents.
